STOCKING BOARDING MACHINE

Fredrick G. Kommrusch, Milwaukee, Wis.

Application November 22, 1937, Serial No. 175,875

20 Claims. (Cl. 223—112)

This invention relates to a stocking boarding machine. In the manufacture of stockings, the stockings come from the dyeing department to the boarding machine in a moist condition, and in the 5 boarding department they are dried and put into a salable condition.

In one process in the manufacture of stockings, the stockings are placed on boards by two operators who stand up. The first operator pulls the 10 cuff over the board and sets the toe and heel, and the second operator pulls the stocking down its entire length over the board and sets the back seam and smooths the cuff by hand. The machine thereafter causes the board to travel around a 15 closed track through a drier to a stocking remover which pulls the stocking from the board. The operators heretofore had to position the entire length of the stocking on the board and smooth out all portions thereof, including the cuff 20 of the stocking, and it required extensive movements of the hands of the operators and also made the process comparatively slow, even with the most skillful operators, and also frequently resulted in tearing or damage of the stocking due 25 to the fact that with the speed required of the operators it was extremely difficult to secure the exact tensioning desired of the stocking on the board.

This invention is designed to provide a stocking 30 boarding machine which reduces the number of operators needed, requiring only a single operator, and allows such operator to be seated instead of requiring a standing position because the machine presents the board in front of the operator 35 in a substantially horizontal position at table height, which increases production, and in which fewer movements are required of the operator.

Further objects are to provide a stocking boarding machine which reduces the chances of tearing 40 or injuring the stocking, which insures a predetermined definite tension for the stocking when it is finally stretched during its positioning on the board, and which brushes out the stocking, particularly the cuff, thus insuring the correct semi- 45 automatic positioning of the stocking.

In greater detail, further objects of this invention are to provide a stocking boarding machine in which a seated operator takes the hose by the cuff, finds the seam by feel, pulling the cuff over 50 the then protruding foot portion of the board, and places the cuff over stationary cuff supports, the machine causing the board to dwell during this portion of the operation. The machine thereafter automatically clamps the cuff to the cuff 55 support. During the dwell and clamping, the op-

erator sets the toe and heel, the machine thereafter projecting the board outwardly into the stocking, the operator, with a sweep of her hands, insuring the positioning of the back seam in a full-fashion stocking at the edge of the board, 5 the machine simultaneously with any slight adjusting operations of the operator continuing the projecting of the board into the stocking until a predetermined degree of tension is reached, and thereafter automatically releasing the stocking 10 from the cuff support.

Further objects are to provide a machine having the characteristics hereinabove enumerated in which a reciprocating head provided with a protecting hood reciprocates forwardly over and 15 beyond the cuff support and thereby places a shielding hood over the cuff support prior to the automatic clamping of the cuff to the cuff support, the hood being effective to push the operator's hands out of the way in the event the operator 20 has them out of position, thereby insuring the maximum safety for the operator.

Further objects are to provide a stocking boarding machine which after automatically clamping the cuff of the stocking to the cuff support, projects the board into the stocking while the cuff of the stocking is held stationary, and after a pre-determined tension has been secured for the stocking, automatically releasing the stocking and simultaneously causing a pair of brushes to come 30 into operation and brush out the upper portion of the stocking, particularly the cuff and the adjacent portion of the stocking, so as to insure a 35 smooth, unwrinkled positioning of the stocking on the board without any danger whatsoever of tearing the stocking.

An embodiment of the invention is shown in the accompanying drawings, in which:

Figure 1 is a diagrammatic plan view of the device with parts broken away and parts omitted. 40

Figure 2 is an enlarged horizontal view of the reciprocating head and the adjacent portions of the track and associated mechanism, with parts in section and parts broken away.

Figure 3 is a vertical elevation, partly in section 45 and partly broken away, of the structure shown in Figure 2.

Figure 4 is a plan view of a portion of the tracks with the head and other parts of the mechanism removed, one of the carriages being 50 shown in full lines with the board sectioned off, other positions of the carriage being shown in dotted lines.

Figure 5 is a sectional view showing a part of the operating structure of the head in its re- 55

tracted position, such view corresponding to a section on the line 5—5 of Figure 2.

Figure 6 is a view corresponding to Figure 5 showing the head in its fully advanced position with the clamping fingers clamping the cuff portion of the stocking to the cuff support.

Figure 7 is a further view of the operating head showing the position of the parts with the clamping fingers released and with the brushes in operation.

Figure 5a is a detail fragmentary sectional view on the line 5a—5a of Figure 2, such view corresponding to the position of the parts shown in Figure 5.

15 Figure 6a is a view similar to Figure 5a with the position of the parts as in Figure 6.

Figure 7a is a view corresponding to Figure 5a with the position of the parts as shown in Figure 7.

20 Figure 8 is a fragmentary detail of the switch which controls the solenoid and brush driving means.

Figure 9 is a fragmentary sectional view on the line 9—9 of Figure 2.

25 Figure 10 is a sectional view on the line 10—10 of Figure 2, that part of the track 4 showing in such figure being shown in elevation.

Figure 11 is a sectional view on the line 11—11 of Figure 1.

30 Figure 12 is a sectional view on the line 12—12 of Figure 11.

Figure 13 is a fragmentary sectional view on the line 13—13 of Figure 2.

35 Figure 14 is a sectional view approximately on the line 14—14 of Figure 3.

Figure 15 is a diagrammatic view showing the electrical circuits to the motor and solenoid.

40 The machine comprises a closed track which may be rectangular and which may have a main portion 1 extending along the front of the machine, a portion 2 extending through the drier 3, and connecting end portions 4 and 5. The track is shown in greater detail in Figure 12, from which it will be seen that it comprises a central rail 6 and upper and lower rails. The central rail 45 projects inwardly.

45 This track is adapted to receive and guide a plurality of carriages 7. These carriages have the upper and lower plates, as shown in Figure 12, and of rectangular construction, as may be seen from Figure 4, and also have a rectangular inner block or plate 8 which is set at an angle to the upper and lower plates, as indicated in Figure 4. These carriages each have swivelly mounted thereon the stocking boards indicated at 9 and shown most clearly in Figure 2.

50 These stocking boards are carried by a spindle 10 which is pivotally mounted within the bearing 11, such bearing being counterweighted at 12 and provided with a laterally extending pivot pin 13, which is rotatably mounted within the angularly set bearing 14, such bearing 14 being rigid with the carriage 7. The shaft or pivot member 13 carries rollers 15 at its outer end and the spindle 60 10 carries a finger 16 at its outer end.

55 The carriage and the stocking boards are of the conventional and well known construction. The carriage is provided with a downwardly projecting pin 17, see Figure 12, which is provided with a roller 18. This roller is engaged by cams located beneath the tracks and is advanced along the track in a counter-clockwise direction, as viewed in Figure 1. Two of these cams have been shown. For example one of the cams is indicated by the reference character 19 in Figure 4 and

advances the carriages along the portion 1 of the track. Another of the cams is indicated at 20 in Figure 4 and advances the carriages along the portion 4 of the track. These cams are carried by shafts extending beneath and lengthwise of the tracks, two of the shafts being indicated in Figure 4 at 21 and 22. The shafts are driven by any suitable source of power, not shown, and operate simultaneously as they are connected by gearing, as shown, for instance, in Figure 4 at 23. 10 The carriage, when it leaves the cam of one section of the track, is received and advanced by the cam of the next section of the track in a well known manner.

15 All of the cams, with the exception of the cam 19, may be of conventional construction. The cam 19, however, as shown in Figure 3, is provided with a straight portion lying in a plane at right angles to the axis of the shaft 21, as shown in Figure 3 and indicated at 24, so as to provide 20 a dwell for the carriage at this point.

The shaft 21 is also provided with a drum 25, see Figures 3 and 9, such drum being of a smaller diameter than the cam 19 and being provided with outwardly projecting cams 26 and 27 for 25 a purpose hereinafter to appear. Also it is to be noted from Figures 3 and 9 that the cam 19 is itself provided with an angularly set block or cam 28 whose purpose will later appear.

Assuming that a stocking board 9 is in the full 30 line position shown in Figures 1 and 2, it will be seen that the continuous rotation of the cam 19 will advance the board until it occupies the position 9a in Figure 1. At this time the carriage is at the straight portion of the cam 24 and a 35 dwell is allowed the board. The operator, who is seated on a stool 29, Figure 1, takes the hose by the cuff, finds the seam by feel, pulling the cuff over the then protruding foot portion of the board, and places the cuff over stationary cuff 40 supports, the machine causing the board to dwell during this portion of the operation. The machine thereafter automatically clamps the cuff to the cuff support. During the dwell and clamping, the operator sets the toe and heel, the machine 45 thereafter projecting the board outwardly into the stocking, the operator with a sweep of her hands, insuring the positioning of the back seam in a full-fashion stocking at the edge of the board, the machine simultaneously with any 50 slight adjusting operations of the operator continuing the projecting of the board into the stocking until a predetermined degree of tension is reached, and thereafter automatically releasing the stocking from the cuff support.

55 This cuff supporting means is shown in plan view in Figures 1 and 2 and in sectional view in Figures 5, 6 and 7, and it consists of a pair of stationary projecting jaws or plates which preferably have ears 30' projecting from its ends, as shown in Figures 1 and 2, so as to assist in holding the cuff of the stocking in place.

60 Preferably a pair of rollers or other guiding means indicated at 31, see Figures 5, 6 and 7, are provided for guiding the board 9, such guiding action being shown particularly in Figures 6 and 7. Additionally the cuff supporting means is provided with cam like portions 32 which assist in guiding the board 9 in between the lips or stationary jaws 30 of the cuff supporting means. This cuff supporting means is preferably of U-shape, as shown most clearly in Figure 10, so as to allow the board 9 to swing outwardly at the 70 corner portion of the track from the position 75

marked 9b, where it is fully extended, to the position marked 9c in Figure 1.

Referring to Figure 10, it will be seen that the two supporting portions 30 are rigidly joined by 5 a spacing block 33 at one end and the lower one is supported by a pillar or arm 34 at the other end from the track 4.

At the termination of the dwell, the board moves from the position 9a to 9b and is projected 10 into the stocking, the operator meanwhile making any minor adjustments that may be needed, as by a sweep of her hand she may assist in positioning the back seam along the back of the board. The cuff of the stocking is clamped to 15 the cuff support in an automatic manner which will hereinafter be described and is later automatically released therefrom when the tension of the stocking reaches a predetermined point, to thus preclude the possibility of tearing or 20 injuring the stocking.

A reciprocating head is provided and comprises a slide 35 which is guided by guides 36, see Figures 3 and 9. The frame of the machine is cut out, as indicated at 37, see Figures 3 and 9, and 25 the slide 35 is also provided with a cut-out 38, see Figure 9, through which a lever 40 projects, the lever being provided with a pointed lower end adapted to be latched behind the notch 41 or the notch 42 of a latch lever 43. The latch lever 30 is spring urged upwardly, as indicated, and is adapted to be retracted by a solenoid 44 or other magnetic member having a lost motion connection 45. The lever 40 is rigidly attached to one of the sleeves 46. The shafts 46 are arranged one 35 above the other and are of tubular construction and are operatively connected by means of gearing 47 so that they simultaneously rotate in reverse directions for a part turn whenever the lever 40 is rocked in a manner hereinafter to appear, the lever 40 being urged in a clockwise direction by spring means as indicated in Figure 9.

The front end of the shafts 46 are each provided with bevelled gears 48 which mesh with bevelled gears 49, such latter being rigidly attached to a pair of parallel clamping finger rock 45 shafts 50 arranged one above the other. The rock shafts 50 are carried within bearing sleeves 51 which are in turn mounted within bearings 52 carried by frames 53 which are spaced apart and 50 arranged one above the other and are rigidly carried by the rigid outer sleeves 54, see Figure 2, the sleeves 54 being in turn rigidly secured to the block 55 which is carried by the slide 35, see Figures 2 and 9.

55 U-shaped arms 56, see Figures 2, 5, 6, 7 and 13, are provided with hubs 57 which are pivotally mounted on the sleeves 51. The U-shaped frames 56 are therefore adapted to be rocked about axes coaxial with the shafts 50. Each of the U- 60 shaped frames carries a brush 58 and the shafts 59 of the brushes extend outwardly to one side of the U-shaped frames and are each provided with bevelled gears 60 which mesh with gears 61 carried by short shafts 62 which are joined by 65 means of a universal joint with the shafts 63, such last mentioned shafts being arranged within the sleeves 46. The shafts 63 are provided with gears 64 which mesh and one of the shafts is provided with a gear 65 which is connected to the 70 gear 66 of the driving motor 67.

This motor 67 is adapted to be started and stopped when it is desired to rotate the brushes 58 or allow the brushes to remain idle. Obviously, instead of starting and stopping the motor, 75 an electromagnetic or other clutch could be used

without departing from the spirit of this invention. The motor 67 is mounted in the reciprocating head and supported from the slide 35, as shown most clearly in Figure 3. The slide is urged to the left, as viewed in Figures 2 and 3, by 10 means of the spring 68 and if desired, a cushion stop 69 or other suitable means can be provided for taking up the shock when the head is retracted under the influence of the spring.

The head in its inactive position is shown in 10 Figure 3. It is provided with a hood 70 which is slotted and allows the cuff supporting means 30 to project therefrom when the head is in its retracted position. Means in the form of a cam controlled lever 71, see Figure 3, is provided and 15 is pivoted, as indicated at 71', to a stationary part of the machine and is connected by means of a link with the head to draw the head to the right, as viewed in Figure 3, against the action of the spring 68 when the roller 72 carried by the lever 20 71 is engaged by the cam block or auxiliary cam 25 28 carried by the cam 19.

When the carriage is rocked to the right, as viewed in Figure 3, it is locked in its extreme forward position by means of the spring pressed finger 25 73, see Figure 11, which passes upwardly through the frame 36 and projects upwardly behind the carriage and thus holds the carriage in place. This spring pressed finger is retracted by means of a cam roller 74, see Figure 11, which 30 rides over a cam portion 75 carried by each of the stocking board carriages 7.

The tripping or release of the carriage occurs after the operation on the stocking is completed for a given board form, and when the carriage 35 of the next succeeding board form comes into position to operate the cam roller 74 of Figure 11, attention being directed to Figure 1 to see the general position of this cam roller.

When the head is in its extreme forward position, the lever 40 is above the latch lever 43 and the cam roller 76 carried by a projection of the lever 43 is in line with the cam 26, see Figure 9. Further the cam roller 77 of a lever 78 is in line with the cam 27. The lever 78 is spring urged 45 in a counter-clockwise direction and is provided with a projecting portion 79 which, when the head is in its extreme forward position, is adapted to strike the lever 40 when the cam roller 77 is actuated by the cam 27 to rock the lever 40 to the 50 right and thereby rotate the tubular shafts 46 to cause clamping fingers 80, see Figures 2, 5, 6 and 7, which are carried by the shaft 50 to clamp the cuff of the stocking to the stationary cuff support 30. 55

When the head is in its retracted position, the parts are as shown in Figure 5 and when in its forward position, the parts are as shown in Figure 6 or 7. The shafts 50 have a squared intermediate portion 81, see Figures 2, 5, 6 and 7, and these intermediate squared portions pivotally support the clamping fingers 80. Such fingers are urged towards clamping position by means of springs 82 mounted within recesses in the shafts 81 and 60 65 the tension of the springs is controlled by the screw plugs 83.

When the shafts 81 are rocked through the medium of the lever 40, see Figures 5, 6, 7 and 9, the fingers 80 are rocked into the position shown in 70 Figure 6 and clamp the cuff of the stocking to the stationary cuff support 30. The shafts 50 are provided with hub portions which have dogs or fingers 84, see Figures 2, 5a, 6a and 7a, which are received within notches 85 formed in the hubs 75

or sleeves 57, which latter are rigid with the U-shaped arms 56, see Figures 2, 5a, 6a and 7a.

The U-shaped arms 56 are spring urged inwardly by means of the springs 86, see Figure 13, 5 so that the brushes 58 are normally urged inwardly by means of the springs 86. The springs 10 may or may not be adjustable as desired. They are prevented from moving inwardly when the dog 84, see Figure 5a, is in the position shown in 15 such figure and thus restrains the hub 57, which is rigid with the U-shaped frame 56, see Figure 2, from rocking to a position to move the brushes 20 inwardly into engagement with the stocking, such stocking being omitted from Figure 2 and being 25 indicated at 87 in Figures 6 and 7, the cuff portion of the stocking being sectioned heavier than the body portion thereof. It is apparent that 30 when the lever 40 is rocked in a counter-clockwise direction by the projection 79 of the lever 78, 35 see Figure 9, that the lugs 84 are moved in a clockwise direction, as viewed in Figures 5a, 6a and 7a, so that the parts occupy the position shown in 40 Figure 6a when the lever 40, Figure 9, engages behind the notch 41. This causes the brushes 45 58 to move into position to engage the stocking, as in Figure 6 which corresponds to the section 5a.

After the clamping fingers 80 have clamped 30 the cuff of the stocking to the cuff support 30, as shown in Figure 6, the board 9, which up to this time has remained stationary, now moves forward 35 as the straight portion of the cam 24, see Figure 3, has passed the carriage of that board and consequently the board is projected forwardly or to 40 the right, as viewed in Figure 6, and projected into the stocking while the cuff of the stocking is held securely locked to the cuff support 30 by means of the spring pressed fingers 80, such 45 spring pressed fingers being provided with cushioned faces of any suitable material, such as leather for instance and as indicated in Figures 5, 6 and 7.

In order to prevent excessive tension being 45 imparted to the stocking an automatic release is provided which includes a feeler finger or bar 88, see Figures 5, 6 and 7, which is carried by a lever 89 which is urged in a counter-clockwise direction by means of the adjustable spring 90. The spring is purposely made adjustable so that 50 the tension at which the feeler finger 88 will respond may be adjusted to the particular needs of the type of stocking handled by the machine. Obviously when the tension at the cuff portion 55 of the stocking, see Figure 6, arrives at a predetermined point, it will cause the lever 89 to rise and will release the latching cam 91 of the switch arm 92.

This switch arm 92 is urged by means of the 60 spring 93, see Figure 8, towards switch closed position. The switch arm may be of any suitable construction. For instance, it may be of insulating material and may carry an adjustable contact 94 which is adapted to engage the stationary contact 95. These contacts control the 65 circuit of the solenoid and motor, as shown in Figure 15, and when the switch is closed, the circuit to the motor 67 and solenoid 44 is completed. Any other suitable type of switch could, of course, be employed without departing from the spirit 70 of this invention.

The closing of the switch causes the solenoid 75 to depress the latching lever 43 a limited extent and allows the lever 40 to move from the notch 41 to the notch 42, see Figure 9. This allows release of the clamping fingers as the lever 40 con-

trols the position of the clamping fingers, as hereinbefore described, and allows them to move to the position shown in Figure 7. This corresponds to the sectional view 7a and it will be seen that the dog 84 carried by the shafts 50 has not 5 yet moved the hubs 57 against the action of the springs urging the brushes inwardly and indicated in Figure 13 at 86. The dog 84 has merely 10 moved over to the other side of the slot 85 of the hub 57, as shown in Figure 7a. Preferably 15 the dogs are provided in duplicates at opposite ends of the squared portions 81 of the shafts 50, see Figure 2.

The motor operates and drives the brushes 58 so as to brush out the cuff and adjacent portion 15 of the stocking 87 as the board continues to move outwardly, the parts being in the position shown in Figure 7. When the board has moved to its extreme position so that the cuff of the stocking 87 has passed from between the brushes 20 58, the cam 26 will engage the cam roller 76, see Figure 9, and depress the latching lever 43, thus completely releasing the lever 40 and allowing it to move into the position shown in Figure 9 and thus rocking the shafts 50, together with 25 their squared finger carrying portions 81, to the position shown in Figures 5 and 5a, and thus rocking not only the clamping fingers to a widely separated position, but also the U-shaped frames 56 with the brushes 58. 30

It is to be noted that immediately upon the forward motion of the head, the hood 70 of the head moves past the stationary cuff support 30 and will thus push the operator's hands out of the way if she has them in the wrong position 35 at this portion of the cycle. The brushes and clamping fingers and electric switch are all housed by the hood 70.

When the parts rock outwardly, as shown in 40 Figure 5, it will be seen that the switch arm 92 engages the stop 96, see Figure 5, and opens the switch, the switch being locked in open position by means of the cooperation of the latching cam 91 and the lever 89. This stops the motor 67 and also opens the circuit of the solenoid 43. 45

When the stocking board has arrived at its most extended position as shown at 9b in Figure 1, the carriage is in the right-hand dotted corner of Figure 4 and the cam 20 of the shaft 22 then takes charge of the carriage and moves it along the track 4. The cam 20 is of conventional construction and in accordance with the usual practice, a cut away hub 97 is provided adjacent the gear 23 of the shaft 21 to allow the passage therethrough of the end of the cam 20. 50 A similar cut away portion is provided in the hub of the gear 23 on the shaft 22 to allow the passage therethrough of the cam 19, though such cut away portion would be hidden in the 55 position of the parts shown in Figure 4. 60

The board now moves laterally from the hood along the track 4. At a short distance from the hood, it will be noted that the upper and lower rails of the track 4, which were cut away, now approach each other and the inner rails 98 of 65 the track 4 are cut away so that the upper and lower portions of the carriage, which are most clearly shown in Figure 12, are now guided by the upper and lower rails of the track 4, thus turning the board into the position shown at 9c 70 in Figure 1. Thereafter any suitable means, such as the cam means 99, 109 and 131, are employed to raise the board into an upright position and turn the board with its plane coaxial 75 with that of the track 4. The board now enters 75

the dryer 3 and progresses along the track 2 to the track 5, suitable cams being provided for causing this progress of the board along the tracks.

5 When the board arrives at the position marked 9d, a stripping means 102 of conventional construction catches the foot portion of the stocking and strips it from the board. Thereafter the carriage travels along the track 1 and 10 passes cam mechanism of any suitable type, such as diagrammatically indicated at 103, which engages the members 15 and 16, see Figures 1 and 2, and turns the board over so that the foot portion is leading the carriage and the 15 toe is pointed outwardly towards the operator, as indicated in Figure 1.

When the board falls over, it rests upon a stationary bar or support 104 and is rocked along this support onto the movable bar or support

20 105. The movable bar or support 105 is pivotally mounted and is provided with a crank arm 106, see Figures 2 and 9, which is connected by means of a link 107 with the lower of the U-shaped frames 53 so that when such U-shaped 25 frame, which constitutes a part of the reciprocating head, moves forwardly, the bar 105 will be rocked out of the way of the approaching carriage.

While one form of cam means has been illustrated for moving the carriages around the 30 closed track, it is obvious that other carriage moving means could be employed without departing from the spirit of this invention.

Further it is obvious that the direction of 35 travel could be reversed if desired and the reciprocating head could be located at the left-hand corner of Figure 1 and the stripping mechanism at the right-hand corner, if so desired. Further, though it is preferable to turn the 40 board over with the toe portion presented towards the operator, it nevertheless is within the province of this invention to have the heel portion of the board towards the operator.

The main steps in the operation will be briefly 45 summarized herewith.

The carriages pass around the closed track, composed of the parts 1, 4, 2 and 5, passing through the dryer, and the stockings are stripped from the forms at the left-hand portion of Figure 1, suitable mechanism, not shown, being provided in the conventional manner for turning the boards down into the position shown at the lefthand portion of Figure 1. Thereafter the boards travel along the track 1 towards the 50 head, and at an intermediate portion of the track are turned over and rotated about their longitudinal axes 180° so that the foot portion of the board leads the carriage and the toe points towards the operator. Thereafter the 55 approaching board is partly projected between the lips of the stationary cuff support 30 and the board is caused to dwell at this point. The operator quickly takes the hose by the cuff, finds the seam by feel, pulling the cuff over the 60 then protruding foot portion of the board, and places the cuff over the stationary cuff supports, the machine causing the board to dwell during this portion of the operation.

The head now moves forward and the cuff is 65 clamped to the cuff support and the brushes move down into engagement with the stocking. The stocking is held locked to the cuff support and the board is projected forwardly into the stocking, the operator, with a sweep of her hands, 70 setting the back seam. The board continues to

project forward until the tension of the stocking arrives at a predetermined point and actuates the feeler finger 88, see Figure 6, to release the switch and allow such switch to close the circuit of the solenoid and of the motor or of a 5 magnetic clutch connected to a constantly running motor, not shown.

The clamping fingers 80, see Figure 7, are now released in the automatic manner hereinbefore described, thus releasing the stocking from the 10 cuff support, and the brushes are now in operation and brush out the cuff of the stocking and the adjacent portions of the stocking while the board continues forwardly. The final position of the board is beyond that shown in Figure 7 15 so that the cuff portion of the stocking is drawn completely forwardly from between the brushes. Thereafter the brush holders are rocked outwardly into the position shown in Figure 5 and the switch is opened, thus opening the circuit of 20 the motor and the solenoid.

While the board is being projected outwardly and the stocking is clamped to the cuff support, the operator may make any minor adjustments she finds necessary. By a sweep of her hands, for 25 instance, she may position the back seam along the rear edge of the board.

Thereafter the board, with the stocking properly stretched thereon, is moved along the track 4 30 to the dryer.

It is to be noted that when the board approaches the head, that it is in the approximate position shown at 9e in Figure 2 and that the carriage is in the dotted line position shown at the left-hand portion of Figure 4, such carriage being 35 guided by engagement of the top and bottom portion 7 thereof with the outer portion of the track 1. Immediately following this, the intermediate portion 8 of the carriage is engaged by the inner rails 6 of the track 1 and the board is turned 40 into the full line position shown in Figure 2, such board sliding along the stationary support 104 and the movable support 105, which latter is in alignment with the stationary support at this time, the reciprocating head being stationary 45 at this time and at the left-hand portion of its travel, as viewed in Figure 2.

It will be seen that a novel form of stocking 50 boarding machine has been disclosed by this invention in which the number of operators required is reduced, in which the production can be speeded up or, in other words, a greater number of stockings handled, and which avoids danger of excessive stretching of the stocking or tearing thereof when it is positioned on the board, 55 the machine having the automatic feeler finger and release of the clamping fingers so that when the board has been projected into the stocking and a sufficient tension produced in the stocking, the feeler finger causes automatic release of 60 the cuff from the stationary cuff support.

It will be seen further that no harm can come 65 to the operator as the clamping fingers, brushes and switch are housed in the reciprocating head and the housing of the head will push the operator's hands out of the way in the event she does not have them in the correct position at the time the head starts on its forward travel. Additionally, less fatigue is caused the operator as she does not have to make extended motions and also may 70 remain seated during the entire process.

It will be seen further that the machine, though 75 accomplishing the above results, is of relatively simple construction and though positive drives are provided for the carriages, nevertheless the 75

automatic release of the stocking insures the satisfactory handling of the stocking without danger of excessive stretching or of tearing.

While the expression "stocking" has been used through the description, it is to be understood that the term is not to be construed in its most limited sense but it intended to cover any form of stocking or sock for which it may be desired to use the machine.

10. While rotary brushing means have been shown and described, it is to be distinctly understood that this invention is not limited to the specific type of cuff smoothing means shown, but any other type of cuff smoothing means could be employed without departing from the spirit of the invention.

Although this invention has been described in considerable detail, it is to be understood that such description is intended as illustrative rather than limiting, as the invention may be variously embodied and is to be interpreted as claimed.

I claim:

1. In a stocking boarding machine, a stocking board, a carriage for said board, cuff holding means for temporarily holding the cuff of a stocking, and means for advancing said carriage and inserting said board into the stocking while the cuff of the stocking is held by said cuff holding means.

30. 2. In a stocking boarding machine, a stocking board, a carriage for said board, a cuff holder for temporarily holding the cuff of a stocking, and means for causing relative motion between said board and said cuff holder while the cuff of the stocking is held by said cuff holder to automatically insert said board into the stocking.

35. 3. In a stocking boarding machine, a stocking board, a carriage for said board, cuff holding means for temporarily holding the cuff of a stocking, means for advancing said carriage and inserting said board into the stocking while the cuff of the stocking is held by said cuff holder, said means including dwell producing means for causing a dwell of said board after said board has projected a part of the way only from said cuff holding means.

40. 4. In a stocking boarding machine, a stocking board, a carriage for said board, cuff receiving and holding means for receiving and temporarily holding the cuff of a stocking, cam means for advancing said carriage to project said board through said cuff holding means, said cam means having a portion for producing a dwell after the foot portion of said board has passed said cuff holding means to allow the positioning of a stocking on said foot portion and on said cuff holding means, said cam means subsequently projecting said board outwardly into said stocking while said stocking is held by said cuff holding means.

45. 5. In a stocking boarding machine, a stocking board, a carriage for said board, cuff holding means for temporarily holding the cuff of a stocking, and means for advancing said carriage and guiding said board through said cuff holding means into the stocking while the cuff of the stocking is held by said cuff holding means.

60. 6. In a stocking boarding machine, a stocking board, a carriage for said board, cuff holding means for temporarily holding the cuff of a stocking, means for advancing said carriage and guiding said board through said cuff holding means into the stocking while the cuff of the stocking is held by said cuff holding means, and

automatically operating means for smoothing out the stocking on said board.

7. In a stocking boarding machine, a stocking board, a carriage for said board, cuff holding means for temporarily holding the cuff of a stocking, means for advancing said carriage and guiding said board through said cuff holding means into the stocking while the cuff of the stocking is held by said cuff holding means, a pair of brushes positioned on opposite sides of said cuff holding means, and automatically operating means for bringing said brushes into engagement with a stocking on said stocking board and for moving said brushes to brush out the stocking.

10. 8. In a stocking boarding machine, a stocking board, a carriage for said board, cuff holding means for receiving and temporarily holding the cuff of a stocking, automatically operating clamping fingers for clamping the cuff to said cuff holding means, means for advancing said carriage and inserting said board into the stocking while the cuff of the stocking is held by said cuff holding means, and automatically operating means for releasing said fingers, whereby said cuff will be drawn from said cuff holding means upon the completion of the travel of said board.

15. 9. In a stocking boarding machine, a stocking board, a carriage for said board, cuff holding means for receiving and temporarily holding the cuff of a stocking, automatically operating clamping fingers for clamping the cuff to said cuff holding means, means for advancing said carriage and inserting said board into the stocking while the cuff of the stocking is held by said cuff holding means, and automatically operating means responsive to the tension of the stocking for releasing said fingers to allow the cuff to be drawn from said cuff holding means by the advancing board when the tension of the stocking has reached a predetermined value.

20. 10. In a stocking boarding machine, a stocking board, a carriage for said board, cuff holding means for temporarily receiving and holding the cuff of a stocking, means for advancing said carriage and inserting said board into the stocking while the cuff of the stocking is held by said cuff holding means, clamping fingers for temporarily clamping the cuff to said cuff holding means, and a tension responsive member responsive to the tension of the stocking, and electromagnetic means controlled by the tension responsive member for releasing said fingers when the tension of the stocking on the stocking board reaches a predetermined value.

25. 11. In a stocking boarding machine, a stocking board, a carriage for said stocking board, a cuff holder for receiving and temporarily holding the cuff of a stocking, a reciprocating head, means for reciprocating said head outwardly, clamping fingers carried by said head for clamping the cuff of the stocking to said cuff holder, means for advancing said carriage and guiding said board into the stocking while the cuff is held on said cuff holder, and tension responsive means for releasing said fingers when the tension of the stocking arrives at a predetermined value.

30. 12. In a stocking boarding machine, a stocking board, a carriage for said stocking board, a cuff holder for receiving and temporarily holding the cuff of a stocking, a reciprocating head, means for reciprocating said head outwardly, clamping fingers carried by said head for clamping the cuff of the stocking to said cuff holder, means for advancing said carriage and guiding said board into

- the stocking while the cuff is clamped to said cuff holder, tension responsive means for releasing said fingers when the tension of the stocking arrives at a predetermined value, rotary brushes carried by said reciprocating head, means for moving said brushes into contact with the stocking of said board, and means for rotating said brushes to brush out a portion at least of the stocking.
13. In a stocking boarding machine, a stocking board, a carriage for said stocking board, a cuff holder for receiving and temporarily holding the cuff of a stocking, a reciprocating head, means for reciprocating said head outwardly, clamping fingers carried by said head for clamping the cuff of the stocking to said cuff holder, means for advancing said carriage and guiding said board into the stocking while the cuff is clamped to said cuff holder, tension responsive means for releasing said fingers when the tension of the stocking arrives at a predetermined value, rotary brushes carried by said reciprocating head, means for moving said brushes into contact with the stocking of said board, means for rotating said brushes to brush out a portion at least of the stocking, and automatically actuated means for moving said brushes away from said board after said board has carried the stocking past said brushes.
14. In a stocking boarding machine, a stocking board, a carriage for said stocking board, a cuff holder for receiving and temporarily holding the cuff of a stocking, a reciprocating head, means for reciprocating said head outwardly, clamping fingers carried by said head for clamping the cuff of the stocking to said cuff holder, means for advancing said carriage and guiding said board into the stocking while the cuff is clamped to said cuff holder, tension responsive means for releasing said fingers when the tension of the stocking arrives at a predetermined value, a pair of rotary brushes carried by said reciprocating head and normally spaced apart, means for moving said brushes towards each other into engagement with the stocking, and means for rotating said brushes after said clamping fingers have released the cuff of the stocking and while said board is moving outwardly whereby said brushes will brush out the cuff of the stocking.
15. In a stocking boarding machine, a stocking board, a carriage for said stocking board, a cuff holder for receiving and temporarily holding the cuff of a stocking, means for advancing said carriage and projecting said board through said cuff holder into the stocking, a head mounted for reciprocation, means for moving said head forwardly, said head having clamping means for clamping the cuff of the stocking to said cuff holder and having means for smoothing the stocking on said board, means for locking said head in its forward position, and means for releasing said head after said board has moved the cuff of the stocking past the smoothing means.
16. In a stocking boarding machine, a stocking board, a carriage for said board, a cuff holder having spaced lips over which the cuff of a stocking is adapted to be positioned, means for advancing said carriage and projecting said board through said cuff holder into a stocking, a reciprocating head, clamping fingers carried within said head and adapted to clamp the cuff of a stocking to said cuff holder, spaced rocking frames mounted within said head, rotary brushes carried by said frames and adapted to be moved into engagement with said stocking, and means for rotating said brushes to brush out the stocking as said board is advanced, and tension responsive means for releasing said fingers when the tension of the stocking reaches a predetermined value.
17. In a stocking boarding machine, a stocking board, a carriage for said board, a cuff holder for temporarily receiving the cuff of a stocking and having spaced jaws, means for advancing said carriage and guiding said board between the spaced jaws of said cuff holder, a reciprocating head, means for moving said head forwardly with respect to said cuff holder, rocking frames carried by said head, clamping fingers and rotary brushes carried by said rocking frames, said clamping fingers being adapted to hold the cuff of a stocking on the cuff holder, means for rocking said frames towards said board, and means for rotating said brushes to smooth out the stocking on said board, said fingers automatically releasing the stocking when a predetermined tension has been imparted to the stocking, said brushes coming into operation after the release of said fingers.
18. In a stocking boarding machine, a stocking board, a cuff holder for receiving the cuff of a stocking, means for holding the cuff of the stocking to said cuff holder, means for projecting said board through said cuff holder into said stocking, means for releasing said cuff from said cuff holder, and means for moving said board laterally from said cuff holder.
19. In a stocking boarding machine, a stocking board, a carriage for said board, means for guiding and advancing said carriage, a cuff holder having spaced lips for temporarily receiving the cuff of a stocking, a reciprocating head having clamping jaws and rotary brushes, means for reciprocating said head and for automatically causing said clamping jaws to clamp the cuff of the stocking to said cuff holder, means for projecting said board between the lips of said cuff holder into the stocking, tension responsive means for releasing the cuff of the stocking from said cuff holder when the tension of the stocking reaches a predetermined value, means for moving the brushes into engagement with the stocking and for rotating said brushes after said stocking has been released from said cuff holder, means for moving said board laterally from said cuff holder, and means for retracting said carriage.
20. In a stocking boarding machine, a stocking board, a carriage for said board, a cuff holder for receiving the cuff of a stocking, clamping fingers for clamping the cuff of the stocking to said cuff holder, means for advancing said carriage and projecting said board into said stocking while the cuff is clamped to said cuff holder, and electromagnetic means responsive to the tension of said stocking for releasing said clamping fingers when the tension reaches a predetermined value.

FREDRICK G. KOMMRUSCH.
